UNITED STATES PATENT OFFICE.

JAMES G. HARRISON, OF LAWRENCE, MASSACHUSETTS, ASSIGNOR TO AMERICAN
FIBRE MATTING COMPANY, OF LAWRENCE, MASSACHUSETTS.

YARN AND METHOD OF MAKING SAME.

961,441.

Specification of Letters Patent. Patented June 14, 1910.

Application filed September 20, 1909. Serial No. 518,471.

To all whom it may concern:

Be it known that I, JAMES G. HARRISON, a citizen of the United States, residing at Lawrence, county of Essex, and State of Massachusetts, have invented certain new and useful Improvements in Yarns and the Method of Making Same, of which the following is a specification.

My invention relates to yarn and the method of making the same and also to fabric woven from said yarn; and particularly to a yarn especially adapted for use as a warp thread in weaving and consisting of a strand of paper and a strand of wool, cotton, linen or similar material suitably twisted together.

The object of my invention is to provide a thread as mentioned in which the component parts shall be so secured to each other as to prevent slipping of one upon the other.

A further and particular object of my invention is to provide a thread characterized as above mentioned which shall break even.

Other objects will appear hereinafter.

In carrying out my invention I provide a twisted paper strand and about this twist a strand of the other material to be used. The last mentioned strand is wrapped about the paper strand in the reversed direction from the twist of the paper strand, and as the two threads are twisted together the paper is partially untwisted causing the same to spread or increase in diameter between the convolutions of the other thread, thereby causing the latter to be embedded in the paper without putting undue strain upon either thread to weaken the same.

This prevents the slipping of the component parts and also leads the two threads at a uniform tension so that when in the loom one will not break without the other.

My invention will be more readily understood by reference to the accompanying drawings forming a part of this specification and in which:

Figure 1 is a view of the paper thread before being subjected to the process above mentioned. Fig. 2 is a similar view of both threads ready to be twisted together. Fig. 3 is a similar view of the finished product, and Fig. 4 is a view of a piece of fabric woven from the yarn.

Referring now to the drawings, 1 indicates a twisted paper thread such as I employ in carrying out my invention, and 2 indicates a thread of wool, cotton, linen or other suitable materials. The paper thread is first twisted to a greater degree than it is desired for it to be in the finished product. The two threads are then twisted together in the reversed direction from the twist of the paper thread and as they are twisted together the paper thread is partially or entirely untwisted as desired. This causes the paper to expand or increase in diameter, as at 3, between the convolutions 4 of the other thread, thereby embedding the latter therein. It is obvious that by expanding the paper within the other thread it is not necessary to place greater tension on the latter to embed the same therein.

In Fig. 4 I have illustrated a piece of fabric woven with a thread composed of the yarn above described, said yarn running in one direction while the threads running in the opposite direction may be of any suitable material such as linen, cotton or the like, 5 indicating the latter threads. By dyeing the paper and the wool of different colors an artistic effect is produced and by running several threads of which the paper is dyed of different colors various patterns may be formed in the manner well known in the art and by having the wool of each thread of the same color a soft effect and harmony through the entire fabric is produced.

Having described my invention what I claim as new and desire to receive protection upon is:

The method of producing a composite strand which consists in twisting one thread about another and previously twisted thread in reversed direction and partially or wholly untwisting said previously twisted thread to expand the same.

In testimony whereof I have signed my name to this specification in the presence of two subscribing witnesses.

JAMES G. HARRISON.
